(57) **CLAIM**

The ornamental design for a multidirectional switch, as
shown and described.

DESCRIPTION

FIG. 1 is a front elevation view of a multidirectional switch of
the present invention;

FIG. 2 is a back elevation view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof, with its operating
element pressed down;

FIG. 8 is a front elevation view thereof, with its operating
element oscillatively moved;

FIG. 9 is a perspective view thereof, taken at the front, top,
right side of FIG. 1; and,

FIG. 10 is a perspective view thereof, taken at the front, top,
right side of FIG. 2.
